UNITED STATES PATENT OFFICE.

DELMAR ALBERT STEVENS, OF CHICAGO, ILLINOIS.

SHOE BOX.

Application filed May 28, 1927. Serial No. 194,961.

This invention relates to boxes usually made of pasteboard, and more particularly to a shoe box.

The object of the invention is to provide 5 a novel shoe box adapted to accommodate a pair of shoes either in the sale or dispensing or more particularly, for the purpose of packaging and transporting or carrying the same conveniently and for storing and protecting the shoes when not in use, from dust, 10 scarring or marring and at all times, to permit convenient access to and removal of the shoes from the box.

A further object of the invention is to 15 provide means for separating the shoes so that they will not strike one another and will not be jarred about or require that the shoes be placed in reverse positions on top of one another, thereby obviating the necessity of using tissue paper, for separating 20 a pair of shoes, and in addition to provide means for fastening the cover and for retaining the shoes from displacement therein when being carried. Other objects and 25 advantages of the invention will be apparent as the description proceeds.

In the accompanying drawing:

Figure 1 is a plan view of my novel shoe box with the cover removed and showing 30 the shoes in position.

Figure 2 is a vertical sectional view taken longitudinally in the box with the shoes in position, and

Figure 3 is a perspective view of the box 35 with one end in section transversely thereof.

Referring to the drawings, the box comprises a body portion 4 having the bottom 5, ends 6 and sides 7. The box is of sufficient height to readily accommodate a pair of oxfords or other shoes designated at 8, 40 therein, so that the same may be accommodated upright and thereby obviates the necessity of using tissue paper between the shoes for preventing their contact or disposing the shoes in reverse position one upon 45 the other with the heel and sole of one down and the heel and sole of the other upward as is ordinary. In this respect, the body of the box is made considerably higher than 50 the usual shoe box for storing and holding the shoes on shelves as commonly used in shoe stores and from which the same are removed for sale. Also, the box is of sufficient width to accommodate two shoes side 55 by side either in the same relative position or in reverse positions, that is, with the

shoes pointing in the same direction or with the soles and heels in reverse positions as shall be found most desirable or preferred.

Disposed longitudinally of the box and 60 centrally thereof with respect to the width, is a vertical partition 9, all of the parts being of cardboard or other suitable material and the ends of the partition 9 being 65 bent or flanged at right angles as indicated at 10 in the same or opposite directions and abutting the inside faces of the end walls 6. Of course, the bent ends which are disposed at right angles, that is, the parts 10, may 70 be glued or otherwise fastened to the ends 6 and thus fix the partition in position. Also, it will be noted that the top edge portions 11 of the partition 9 are disposed slightly 75 spaced from the top edge of the body 4 and from the cover 12 which is placed over the open top of the body of the box and has down turned sides or a continuous flange 13 engaging around the ends 6 and sides 7 snugly as shown. The intermediate portion of the partition is preferably recessed as indicated at 14, the recess being preferably 80 centrally located and cut out in concave formation so as to provide a depression permitting convenient access to the shoes for removal by the hand. This recess also accommodates a flexible or other fastening means 85 15, preferably in the form of a shoe-string, cord, or ribbon, the same extending through openings 16 in the sides 7 immediately 90 above the lowest part of the depression or recess 14 so that the shoes are not only retained in position but the ends of the fastenings may be extended up over the down-turned sides or flanges 13 of the cover 12 95 and tied as indicated at 17, thus providing a handle by which the box may be transported and also a means of tying or sealing the box when the cover is in position and for holding the cover thereon.

A shoe box as thus constructed is a very 100 desirable adjunct in the display and sale of shoes and for transporting or carrying and storing the same when not in use. The shoes will be protected from dust or other foreign matter and for scraping against one 105 another when not in use or in transporting the same. This will also obviate the necessity of mashing or squashing the shoes in the box as is customary with result of cracking or other disfiguring thereof.

While I have shown my invention in a 110 preferred form, it is to be understood that

various changes may be made in the construction, proportion and arrangement of the parts and also in the materials used, without departing from the spirit and scope 5 of the invention.

Having thus described my invention what I claim is:

1. A shoe box having a width and length for accommodating a pair of shoes side by 10 side and resting upon the soles and heels in an upright position, a cover for the box, a longitudinal fixed partition within the box for forming a compartment for each shoe, a central recess in the upper edge of the partition so arranged as to allow easy accessibility to the shoes when removing them from 15 the box.
2. A shoe box having a width and length for accommodating a pair of shoes side by 20 side and resting upon the soles and heels in an upright position, a cover for the box, a longitudinal fixed partition within the box

for forming a compartment for each shoe, a portion of the upper edge of the partition being below the top edge of the box and 25 spaced from the cover thereof in order to allow easy accessibility to the shoes in removing them from the box.

3. A shoe box having a width and length for accommodating a pair of shoes side by 30 side and resting upon the soles and heels in an upright position, a cover for the box, a longitudinal fixed partition within the box for forming a compartment for each shoe, a central recess in the upper edge of the partition so arranged as to allow easy accessibility to the shoes when removing them from the box, the upper edge of the partition being spaced from the top of the box, a 35 flexible handle portion extending from the 40 sides of the box over the top thereof.

In testimony whereof I affix my signature.

DELMAR ALBERT STEVENS.
